UNITED STATES PATENT OFFICE.

STRAUD K. WOOD, OF HUTCHINSON, KANSAS.

COMBINED HASP AND SEAL FOR BOX CARS.

Application filed January 24, 1927. Serial No. 163,061.

This invention relates to combined fastening and sealing devices for box cars and the like, and has for its object to produce a simple and efficient mechanism for protecting 5 the fastening element of the seal against accessibility, so that if the seal is broken it can readily be discovered by simply slipping a finger through the loop and pulling thereon, which action can be accomplished and 10 the condition of the seal determined by day or night without necessitating any waste of time by visual inspection. A further object is to produce a fastening mechanism which is protected against accumulation of snow 15 or ice in the fastener to render the withdrawal of the bolt difficult.

With these objects in view, the invention consists in certain novel features of construction and organization of parts as hereinafter 20 described and claimed; and in order that it may be fully understood, reference is to be had to the accompanying drawing, in which:

Figure 1 is a side elevation of a part of a box car equipped with a combined fastening and sealing device embodying the invention.

Figure 2 is an edge view of the same, with the frame post of the car upon which the fastening device is mounted, in section.

Figure 3 is an enlarged section on the line III—III of Figure 1.

Figure 4 is a horizontal section on the line IV—IV of Figure 1.

Figure 5 is a detail perspective view of 35 the fastening slide or bolt.

Figure 6 is a fragmentary perspective view of the upper part of the fastener plate and fastening bolt.

Referring to the drawing in detail, 1 indicates the car post at the left hand side 40 of the door opening, and against which the door 2 is adapted to close. The door is equipped with the customary staple 2^a to which the hasp 3 is hinged, and the hasp is provided with a slot 4 for receiving a staple 5 projecting outward from the lower part of 45 the fastener plate 6 secured by bolts 7 and 8 at its lower and upper ends respectively, to the door post. The door plate is provided near its upper end with a vertical keeper 9 and in a plane below the same, with a pair of angular inturned flanges 10.

A slide 11 extends through the keeper and fits flatly against the side flanges 10 of plate 55 6, and is provided in a plane below the

keeper with a T-shaped rib 12 fitting slidingly in the angle flanges 10. The slide is also provided with an outwardly-projecting shelf 13 fitting in the lower part of and forming a bottom for the keeper 9, and the upper end of the slide is provided with a head 14 to rest upon and close the keeper and limit downward movement of the slide therethrough, the head of the keeper being flanged outward at the left beyond the corresponding side of the keeper, to provide a handle 15 by which the operator can readily effect upward movement of the slide.

The slide is provided with a bolt-extension 16 for engaging an opening 17 of the staple 5, and said bolt above and in proximity to said staple is provided with a perforated arm 18, the staple 5 below said arm being provided with an opening 19.

The fastener plate 6 is provided near its upper end and at one side with a perforated lug 20, to which a padlock 21 may be secured for preventing upward movement of the slide, and a plate 22 fits against the upper end of the fastener plate and rests upon the sides of the keeper 9, and is provided with an opening through which the bolt 8 extends, the plate having a countersunk opening 23 receiving the head of said bolt so that said head shall not interfere with upward movement of the slide when the padlock is not in place, the principal function of the plate 22 being to serve as an abutment for rib 12 and thereby arrest upward movement of the slide after the shelf is made accessible at 85 the upper end of the keeper. It also serves to close the space between the outer face of plate 6 and the inner edge of the head 14 of the slide, so as to prevent snow and hail from entering said space and freezing therein and thus interfering with the free upward movement of the slide when such movement is necessary.

From the foregoing it will be apparent that the bolt extension 16 holds the hasp 100 normally in fastened position and that the engagement of the keeper with the upper end of the slide and the engagement of the T-shaped rib 12 with the flanges 10, guard against any but vertical movement of the 105 slide relative to the fastener plate.

To seal the appliance, the customary or conventional type of sealing strip 23 and sealing strip fastener head 24 is employed, it being noted that the fastening head is 110

received upon the shelf 13 of the slide and within the keeper 9, and hence is inaccessible, the strip extending down through an opening 25 in the shelf and through the 5 arm 18 and staple opening 19, the seal being thus applied before the slide is placed in operative position. After the parts are placed in operative position, the free end of the seal strip is bent upwardly around the 10 outer end of the staple 5 and then slipped up into the fastening head 24 where it automatically fastens in place, this feature of construction being not detailed as the seal shown is of the conventional type and 15 no claim is made to it except in combination with the other features of the device.

Should the padlock be omitted or knocked off or the seal be broken, access of course can be had to the car, because the slide under such conditions is free to be moved upward to withdraw its bolt extension from engagement with the staple 5 preliminary to the disengagement of the latter with the hasp, but after the parts are returned to 25 normal position, it will be impossible for the seal to be refastened, hence anyone slipping a finger through the loop after the strip is again bent upwardly to form a loop as would naturally be attempted in the endeavor to hide the evidence of tampering, 30 a tug on the strip would free the outer portion thereof and indicate at once that the seal had been broken. Should a new seal be substituted for the original,—as would be possible if the padlock was opened,—that fact would be apparent at the proper time because the seals are consecutively numbered and only one seal bears a particular number, and the ordinary person, to steal 35 from a box car or the like, would not, in advance, know the number of a particular seal which he might break and hence would not be prepared to supply a correspondingly numbered seal. With the use of the 40 padlock however, the breaking of the seal merely would not give access to the car, and if the seal was broken without getting access to the car, it would be impossible to replace the seal even if an unauthorized person is equipped to supply a duplicate, as in 45 that case the slide cannot be raised and access to the head of the seal would be impracticable.

From the above description, it will be 50 apparent that I have produced a device which embodies the features of advantage set forth as desirable in the statement of the object of the invention, and which may be modified in minor particulars within the 55 principle of construction and mode of operation involved and also within the spirit and scope of the appended claims.

What I claim is:

1. In a combined fastener and seal, a plate having a keeper and a staple, a slide mounted for longitudinal movement only on the plate and extending through the keeper and staple, and provided with a shelf within the former and a head spaced above the shelf, a seal strip fastening the plate and slide in looped relation and extending through said shelf into the keeper, and a head fastening the ends of the strip together within the keeper between the head and shelf of the slide. 65

2. In a combined fastener and seal, a plate having a keeper and a staple, a slide mounted for longitudinal movement only on the plate and extending through the keeper and staple, and provided with a shelf within the former and a head spaced above the shelf, and resting upon the keeper, locking means for preventing upward movement of the slide, a seal strip fastening the plate and slide in looped relation and extending through said shelf into the keeper, and a head fastening the ends of the strip together within the keeper between the head and shelf of the slide. 70

3. In a combined fastener and seal, a plate having a keeper and a staple, a slide mounted for longitudinal movement only on the plate and extending through the keeper and staple, and provided with a shelf within the former and a head spaced above the keeper, a seal strip fastening the plate and slide in looped relation and extending through said shelf into the keeper, a head fastening the ends of the strip together within the keeper between the head and shelf of the slide, and a plate fastened to the first-named plate in a plane rearward of the head of the slide, to arrest upward movement of the latter when the shelf is accessible at the top of the keeper. 90

4. In a combined fastener and seal, a plate having an upright keeper and a staple below the keeper and angle-flanges between the keeper and staple, a slide having a flanged rib engaging the angle flanges and provided above the rib with a head resting on and a shelf within the keeper, and below the rib with an arm over and a bolt extension extending through the staple, a seal looped through the said arm and staple 110 and extending at its ends up through the shelf into the keeper, and a head within the keeper between the head and shelf of the slide and securing the ends of the strip against withdrawal. 115

In witness whereof I hereunto affix my signature.

STRAUD K. WOOD.
